UNITED STATES PATENT OFFICE.

WILLIAM F. MCKAY, OF LA GRANGE, ILLINOIS.

METHOD OF MAKING PREPARED ROOFING.

1,264,831.

Specification of Letters Patent. Patented Apr. 30, 1918.

Original application filed May 5, 1913, Serial No. 765,445. Divided and this application filed October 19, 1915. Serial No. 56,685.

To all whom it may concern:

Be it known that I, WILLIAM F. MCKAY, a citizen of the United States, residing at La Grange, in the county of Cook and State 5 of Illinois, have invented certain new and useful Improvements in Methods of Making Prepared Roofing, of which the following is a specification.

My invention relates to improvements in 10 prepared roofing material.

One of the objects of my invention is to provide a method for the manufacture of roofing material which shall have the appearance of tile or slate when applied to the 15 roof.

The base of my roofing material is preferably felt or other fabric properly impregnated with a weather-proofing material such as asphaltum, or the like, and having a superposed layer of flaked slate or other like mineral matter overlying the saturated material and pressed thereinto and at intervals provided with a stripe of different or darker color in imitation of separate pieces or 25 plates of slate or tile as they appear when laid upon the roof.

In manufacturing my improved roofing I use a machine through which the felt is continuously passed. It enters the machine 30 from the roll at one end and is discharged therefrom at the other end in the finished product.

In the drawings—

Figure 1 shows a central longitudinal section of a machine of this character;

Fig. 2 is a plan view thereof;

Fig. 3 is an enlarged detail of the construction, part thereof being in section;

Fig. 4 is an enlarged detail in plan view 40 of part of the structure;

Fig. 5 is an enlarged sectional view of part of the machine taken on line 5—5 of Fig. 2;

Fig. 6 is a plan view of a part of the strip 45 as it passes through the machine;

Fig. 7 is a front view of the roof as it will appear when my roofing material is applied thereon; and

Fig. 8 is a sectional elevation of a portion 50 of the roof and the roofing material as it is applied.

In all the views the same reference characters are employed to indicate similar parts.

This is a divisional application from my

copending application, Serial No. 765,445, 55 filed May 5th, 1913, for roofing material.

10 is a roll of felt or other suitable fabric before it passes through the machine, 11 is the felt sheet passing through the machine, and 12 is a tank containing asphaltum 13, or 60 the like, adapted to be heated by steam coil 14. The felt sheet passes over the rollers 15—15' and under the rollers 16—16' so as to be completely submerged in the coating material contained in the tank 12. The material contained in the tank 12 may be of a compound that is adapted readily to saturate the felt and may be heated to such a degree as is found most expedient for this purpose. 17 and 17' are adjustable doctors or 70 scrapers for scraping off the excessive material from the sheet of felt as it passes through the tank. The sheet now passes through another tank 18 which contains a compound 19 made, preferably, of a material to withstand a greater temperature than the material contained in the tank 12, and of a somewhat more mastic or sticky nature. The sheet 11 passes over the rollers 20 and 20' and under the roller 21. This 75 tank also contains steam pipes 22 by which the compound in the tank 18 may be heated to any desirable temperature, and a doctor or scraper 23 is adjustable to bear with greater or less pressure against the under 80 surface of the strip 11 to remove more or less of the deposited material from the under surface of the sheet. A blower 24 is adapted to cool the sheet, or the upper surface thereof, as it passes out of the tank 18 85 and before the deposit of any material thereon. The blower is driven from the pulley 25 by the chain or belt 26. Following the blower is a series of hoppers 27 each provided with reduced outlets 28 and each containing a supply of sand or other suitable 90 granular or flake material 29. The apices or discharge openings are spaced apart a distance corresponding with the distance between the stripes that are to be made on 100 the finished product. Any convenient method of controlling the flow of the sand from the hoppers may be employed. The sheet 11 moves forward toward the right hand side, being driven by the machinery 105 illustrated, consisting of the rollers 36 and 37 driven by the traveling apron 80 carried by the chain 81 that passes over a sprocket

wheel 82, secured to the shaft 83. A belt 85 drives the wheel 84 and thus power is supplied for moving the fabric through the machine. While so moving, small and uniform streams or deposits of sand are made upon the upper surfaces of the sheet. These streams of sand pass underneath the hopper 30 containing a rotating perforated drum 31. The drum is rotated by means of a chain 32 10 from the driving shaft 34 which contains a driving wheel 35. The drum 31 is filled with finely divided slate flakes, or other similar material, and as the sheet passes under this rotating drum a thin coating of slate 15 is deposited upon the upper surface of the sheet. The little ridges or mounds of sand prevent the slate from sticking to that portion of the felt fabric covered by the sand.

20 After the slate has been deposited upon the sheet it is then passed between rollers 36 and 37 which cause the finely divided materials to be partially embedded into the upper mastic surface of the roofing material. The sand, having been deposited upon the material before the slate, is embedded into the mastic material and the color of the asphaltum strikes through the sand making a relatively black stripe. The slate 25 between the stripes, however, is not so discolored and retains its natural appearance. The black intermediate surface being entirely and evenly covered by the slate flakes does not affect the slate color and therefore 30 the finished product contains clearly defined black stripes which, when the strips are applied to the roof, have the appearance of division lines, giving a tessellated effect as in the application of shingles, slate, plates 35 or tiling. This gives to the roof, or other surface covered, a very ornamental appearance.

After the sheet has passed between the rollers 36 and 37, which rollers are adjustable toward and from each other for the purpose of varying the pressure thereon, as by means of a screw 38, it passes under a roller 39 and then over a relatively large wheel 40. This wheel may be located at some remote 45 point so that considerable material may be included between the wheels 39 and the rollers 41 and 42 between which the sheet again passes. The object of passing the sheet over the wheel 40 is to give it time to cool before 50 it passes into the vat 43 which contains a water bath 44. The roller 45 has a tendency to submerge the sheet in the water but it is freely movable into vertical position by the sheet.

60 After the sheet passes through the water vat it then passes between the driving rollers 46 and 47 which are also adjustable by the screw tensioning device 48.

After the sheet has been made, in the 65 manner heretofore described, it may be de-

sirable to cut it into strips of uniform lengths, transversely of the sheet. I, therefore, for this purpose, provide a cutting machine 49 driven by belt 50. The driving shaft 51 upon which is mounted the driving 70 pulley 52 rotates constantly. It carries a spur gear 53 which meshes into a gear wheel 54 that is carried on a shaft 55. The wheel 54 also carries the crank arm 56. Projecting upwardly from the table of the machine 75 are knife guides 57 and 58 within which reciprocate a frame 59, which carries a cutting knife blade 60 and a kerfing blade 61. These blades are adjustable in the frame by means of screws 62. A slotted link 63 80 connects the frame 59 to the crank arm 56. There are two such slotted links, one on each side of the frame, and there are also two crank arms 56 properly driven by the shaft 55. The rollers 46 and 47 are driven 85 by means of two gears 64 and 65 carried by the shafts 67 and 68 respectively. These rollers are rotated periodically by means of the ratchet wheel 69 that is secured to the shaft 68. The slotted link 63, at its lower 90 end, is pivotally connected to a link 70, and this link in turn is connected, as at 72, to an arm 71, which swings on the shaft 68. The link 71 carries a pawl that engages in the ratchet teeth of the wheel 69. A stop 95 pawl 74 prevents the return of the ratchet wheel when moved forward by means of the pawl 73. Now when the shaft 55 is rotated anti-clockwise the crank arm 56 is raised and thereby, through the connecting 100 link 63, the knife frame 69, carrying the knife blades 60 and 61, is raised in the frame 67 and 68 at the same time the ratchet wheel 69 is rotated anti-clockwise, by means of the pawl and ratchet connection, and the 105 rollers 46 and 47 are rotated in such direction as to cause the strip 11 to be moved to the right and to project beyond the blade 60 to the extent desired for the proper width of the finished strip. When the crank arm 110 56 has arrived at its highest position the knives will have reached the uppermost position in the guides 57 and 58 and the sheet 11 will have been moved to its fullest extent under the knife. Now when the shaft 115 55 completes the other half revolution the crank 56 will have moved back to its normal position, that shown in Fig. 3, and the swinging arm 71 will have moved back to its position causing the pawl 73 to move 120 over the ratchet teeth contained in the ratchet wheel 69 without moving the rollers 46 and 47 at the same time the blades 60 and 61 will have descended and the knife 60 will have severed the sheet into strips and 125 the blade 61 will have made a kerf or score into the upper surface of the strip at a pre-determined distance back from its marginal edge for a purpose to be hereinafter described. The strip will then fall from the 130

knife upon the apron 75 from which it will pass to the conveyer 76. There will be sufficient slack of the sheet 11 contained in the tank 43 to permit its forward movement under the knife, at all times. When the sheet is thus moved forward, the roller 45 in the tank 43 may be raised, but as the sheet continues to move, the machine causes more sheet to pass into the tank 43, and the 10 roller 45 will gradually be lowered into the tank.

The kerfing or scoring knife blade 61 has a blunt edge and passes only part of the way through the sheet, sufficiently however 15 to penetrate the slate, thereby providing a kerf or score 77 which extends across the stripes and provides a weakened line or bending edge whereby the marginal portion beyond the score may be folded under the 20 main strip when laying the material on the roof, as shown in Fig. 8. By cutting through the mastic deposit and the finely divided mineral material, the strip may thus be folded without cracking or breaking the 25 fabric.

When laying the shingle simulating material the strip is placed upon the roof and the two finished surfaces are laid one upon the other and nails 79 are driven through 30 the part divided by the kerf or score and the upper marginal edge of the underlying strip and then the major portion of the finished strip 78 is turned back over that portion thereof that has been nailed to the roof support and another strip is thus nailed to its 35 marginal edge, thus providing a joint and protecting the nails, by which the material is secured to the roof, against the effect of moisture and weather.

40 In Fig. 7 the underlying edge of the strip is shown in dotted lines and the nails which penetrate through the two underlying marginal edges of the respective strips are also shown in dotted lines.

45 Having described my invention, what I claim is:

1. The method of making roofing material which consists in continuously depositing a mastic weatherproof material on a 50 continuously moving absorbent sheet; then depositing thereon finely divided granular or flaky material; then applying pressure to said sheet to partially embed said material therein; then cutting the sheet transversely into strips of predetermined lengths.

2. The method of making roofing material which consists in continuously depositing a mastic weatherproof material on a continuously moving absorbent sheet; then 60 depositing thereon finely divided granular or flaky material; applying pressure to said sheet and material; scoring and simultaneously cutting the sheet transversely into strips of predetermined lengths.

65 3. The method of making roofing mate-

rial which consists in continuously depositing a mastic weatherproof material on a continuously moving absorbent sheet; then depositing thereon a plurality of relatively small streams of comminuted material; then 70 depositing on and across the entire upper surface of said sheet, flaky or granular material substantially unaffected in color by the underlying mastic material; then applying pressure to said sheet and deposited material.

4. The method of making roofing material which consists in continuously depositing a mastic weatherproof material on a continuously moving absorbent sheet; then 80 depositing thereon a plurality of relatively small streams of comminuted material; then depositing on and across the entire surface of said sheet flaky or granular material substantially unaffected in color by the underlying mastic material; then applying pressure to said sheet and deposited material; then cutting said sheet into strips of predetermined lengths.

5. The method of making ornamental sheets of material for roofing or the like which consists in continuously moving the sheet; applying thereto while moving a water-proofing adhesive material; then depositing thereon a plurality of separated relatively small streams of comminuted material, leaving intervening spaces with the water-proofing adhesive exposed; then depositing on and across the surface of said sheet and streams a contrasting granular or flaky material substantially unaffected in appearance by said adhesive, then compressing said strip to substantially uniform thickness.

6. A method of making roofing elements which consists in embedding longitudinal stripes of crushed mineral material in the adhesive coating of a sheet of roofing material, and then cutting said sheet transversely to form strips having said stripes cross wise thereon.

7. A method of making roofing elements, which consists in applying an adhesive to the face of an elongated fibrous sheet, embedding lines of crushed mineral material in said adhesive to form longitudinal stripes, and then cutting said sheet transversely to form sections of the same width and length.

8. A method of making roofing elements, which consists in applying an adhesive to the face of an elongated fibrous sheet, embedding lines of crushed mineral material in said adhesive to form longitudinal stripes, and embedding crushed mineral material of another color in the uncoated portions of 120 said adhesive to form intervening bands.

9. A method of making roofing elements, which consists in applying an adhesive to the face of an elongated fibrous sheet, embedding lines of crushed mineral material in

said adhesive to form longitudinal stripes, embedding crushed mineral material of another color in the uncoated portions of said adhesive to form intervening bands, and 5 cutting said sheet transversely into shingle strips.

10. A method of making roofing elements, which consists in applying an adhesive to the face of an elongated fibrous sheet, embedding lines of crushed mineral material in said adhesive to form longitudinal stripes, embedding crushed mineral material of another color in the uncoated portions of said adhesive to form intervening bands, and 15 cutting said sheets into sections each having said stripes and bands crosswise of its length.

11. The method of making roofing elements, which consists of moving an elongated sheet of fibrous material lengthwise, applying thereto a coating of waterproof adhesive substance, passing said sheet under separated streams of crushed mineral material to cause said material to adhere in 20 stripes to said adhesive substance, pressing said material into the said coating, and then cutting said sheet transversely into sections.

12. The method of making roofing elements, which consists of moving an elongated sheet of fibrous material lengthwise, applying thereto a coating of waterproof adhesive substance, passing said sheet under separated streams of crushed mineral material to cause said material to adhere in 30 stripes to said adhesive substance, then passing said sheet through a shower of crushed mineral material of a different color to cause said material to adhere to said coating between said stripes, and removing the surplus crushed mineral material.

13. The method of making roofing elements, which consists of moving an elongated sheet of fibrous material lengthwise, applying thereto a coating of waterproof adhesive substance, passing said sheet under 45 separated streams of crushed mineral material to cause said material to adhere in stripes to said adhesive substance, then passing said sheet through a shower of crushed

mineral material of a different color to cause 50 said material to adhere to said coating between said stripes, and then severing said sheet crosswise into sections of substantially the same length and width.

14. A method of making waterproof roofing, which consists of applying a waterproof adhesive to the face of a fibrous sheet, passing said sheet under separated streams of crushed mineral material to cause said material to adhere in lines to the face of said 60 foundation, and embedding said material in the adhesive coating.

15. A method of making roofing elements, which consists in passing a sheet of fibrous material having an adhesive waterproof coating beneath separated streams of crushed mineral material to cause said material to adhere thereto in lines or stripes, and then passing said sheet under other streams of differently colored grit, to cause said last- 70 mentioned material to adhere to the adhesive coating in other lines or stripes.

16. A method of making roofing elements, which consists in passing a sheet of fibrous material having an adhesive waterproof coating beneath separated streams of crushed mineral material to cause said material to adhere thereto in lines or stripes, then passing said sheet under other streams of differently colored grit, to cause said last- 75 mentioned material to adhere to the adhesive coating in other lines or stripes, removing the surplus grit, and embedding the remaining grit in the said adhesive coating.

17. The method of making roofing elements which consists in embedding conventional patterns of crushed mineral material in the adhesive coating of a sheet of roofing material; then scoring the sheet transversely 80 near one edge and simultaneously cutting 90 the sheet parallel to the scoring, into strips.

In testimony whereof I hereunto set my hand in the presence of two subscribing witnesses.

WILLIAM F. MCKAY.
